Primary Examiner — Susan Bennett Hattan*Assistant Examiner* — Suzanne E Tisdell(74) *Attorney, Agent, or Firm* — Westerman, Hattori, Daniels & Adrian, LLP(57) **CLAIM**

The ornamental design for a front grille for an automobile, as shown and described.

DESCRIPTION

FIG. 1 is a front perspective view of a front grill for an automobile.

FIG. 2 is a front view of a front grill for an automobile.

FIG. 3 is a left side view of a front grill for an automobile.

FIG. 4 is a right side view of a front grill for an automobile; and,

FIG. 5 is a top plan view of a front grill for an automobile. The broken lines in the drawings illustrate portions of the front grill for an automobile that form no part of the claimed design.
